MUSICAL DRUM HOLDER

Emil L. Farnlund, Anaheim, Calif., assignor to Farnlund & Webster Co., Anaheim, Calif., a partnership

Filed May 3, 1965, Ser. No. 85,062

Term of patent 14 years

(Cl. D56—1)

FIG. 1 is an isometric view of a musical drum holder embodying my new design;

FIG. 2 is a left side elevational view, the right side elevational view being a substantially mirror image thereof;

FIG. 3 is a top plan view thereof;

FIG. 4 is a bottom plan view thereof;

FIG. 5 is a front elevational view thereof; and

FIG. 6 is a rear elevational view thereof.

A portion of the design figures is stippled to indicate contrast in appearance.

I claim:

The ornamental design for a musical drum holder, substantially as shown and described.
